UNITED STATES PATENT OFFICE.

CHARLES I. LATTIG, OF ROCHESTER, NEW YORK, ASSIGNOR TO HARRY R. LANGSLOW,
OF ROCHESTER, NEW YORK.

SCHOOL-CHAIR.

1,217,319.

Specification of Letters Patent. Patented Feb. 27, 1917.

Application filed February 17, 1915. Serial No. 8,739.

To all whom it may concern:

Be it known that I, CHARLES I. LATTIG, of Rochester, in the county of Monroe and State of New York, have invented certain new and useful Improvements in School-Chairs; and I do hereby declare the following to be a full, clear, and exact description of the same, reference being had to the accompanying drawings, forming a part of this specification, and to the reference-numbers marked thereon.

My invention has for its object to provide an improved form of school chair in order to afford a construction that is strong in every part, and which may be subjected to hard usage without injury. Another purpose of the construction is to afford a table or desk portion in connection with a chair and arranged in a manner to permit adjustment on the chair in two directions, and thereby accommodate it to different sized persons. Still a further purpose of the construction is to afford an arrangement that makes it possible to construct the framework of the chair of angle or channel iron, reducing the cost of manufacture and also imparting additional rigidity to the structure. To these and other ends the invention consists in certain improvements and combinations of parts all as will be herein-after more fully described, the novel features being pointed out in the claims at the end of the specification.

In the drawings:

Fig. 1 is a side elevation of a chair constructed in accordance with my improvement;

Fig. 2 is a front view of the same;

Fig. 3 is a plan view;

Fig. 4 is a sectional view on the line 4-4 of Fig. 3;

Fig. 5 is a sectional view on line 5-5 of Fig. 4;

Fig. 6 is a side elevation showing the table or desk elevated;

Fig. 7 is a sectional view taken vertically on line 7-7 of Fig. 1;

Fig. 8 is a sectional view on line 8-8 of Fig. 1;

Fig. 9 is a perspective view of the plate which forms a part of the table carrier, and

Fig. 10 is a sectional view on line 10-10 of Fig. 6.

Similar reference characters in the several figures indicate the same parts.

In the embodiment herein shown, the chair comprises rear legs 1 and a back portion 2, which is slotted on one side at 3 and 4 for a purpose that will presently appear. 5 designates the front legs which are connected to the rear legs by the cross pieces 6, and 7 is the seat portion. The back portion may be provided with panels 8 which are of wood secured in any desirable manner, and is constructed preferably of angle iron, as 65 are also the legs and cross pieces.

Arranged for vertical adjustment on the back portion and one of the front legs is a supporting frame for the table or desk, which latter is mounted on a carrier adjustable on the supporting frame, as will appear presently, and to this end I employ a vertically arranged member or angle iron 9, slotted at 10 to permit of its being adjustably attached to one of the front legs. In 75 addition to the vertically arranged member 9, the supporting frame referred to includes a pair of rearwardly extending guides or members which are preferably in the form of channel bars, as designated at 11 and 12, 80 these being rigidly secured to the vertical member 9. Members 11 and 12 are adjustably attached to the back portion of the chair by bolts 13 passing through slots 11 and 12 in the arms 11 and 12 respectively, 85 and are adjustable vertically by means of the aforementioned slots 3 and 4. In order to effect vertical adjustment of the supporting frame, it is necessary to loosen the fastening means of the vertical member 9 and 90 of the rearwardly extending members 11 and 12, the entire frame being then movable either upwardly or downwardly. The upper guide or member 11 is curved, in the manner shown, in order to afford a recess 95 or dished portion 14 to permit free play of the arm of a person in the chair, and at the same time to permit of attaching the member 11 to the back portion of the chair at such a point as to afford maximum rigidity 100 between the back portion and the table supporting frame, the upper member 11 being attached to the back portion preferably at a point nearer to the top of the back than to the seat.

Arranged for lateral adjustment on the supporting frame just described, is a carrier upon which is directly mounted the table or desk portion. The carrier comprises a vertically disposed plate 15 having recesses or 110

channels 16 for engagement with the guides or members 11 and 12. The plate 15 also is provided with flanges 17 which are attached to angle irons 18 arranged on the inner side 5 of the guides 11 and 12. The lugs 19 extend between angle irons 18 and angle bars 20, while lugs 21 are secured to the vertical angle irons 18 already referred to. The angle irons 18 are bent at right angles at 10 their upper ends to form horizontal portions 22, to which are secured the angle bars 20. The vertical member 9, which is adjustable on the forward leg 5, is secured in position by means of bolts 23, and by this 15 means, the supporting frame or carrier for the table or desk can be adjusted to any elevation desired, and held rigidly in such position. The supporting frame or carrier can also be moved in and out on the guide members 11 and 12, its frictional engagement with the guide members being sufficient to hold it in any desired position.

The table or desk is designated at 24 and has attached thereto angle bars 25 which are 25 pivotally connected at 26 to the aforementioned angle bars 20 mounted on the supporting frame. 27 designates links pivotally connected to the forward ends of the angle bars 20, and having their free ends adjustably associated with the angle bars 25 on the table 24. To this end, the bars 25 are slotted at 28, while 29 designates a rod extending through the bars 25 and links 27 respectively. The rod 29 has a fixed head 30 at 30 one end, while 31 designates a sleeve surrounding the rod and arranged between the links 27. 32 designates a second sleeve disposed between the free end of the rod 29 and the adjacent angle bar 25, while 33 is an 35 adjustable nut threaded on the end of the rod and operating, when turned, to tighten the parts and hold the links 27 in fixed relation to the bars 25. By this means, the table 40

or desk 24 can be retained at any desired angle to a horizontal plane, being disposed 45 horizontally when in its lowermost position.

In a chair of this character, it is desirable to provide means for holding a supply of ink in a readily accessible place, and to this end I employ a socket 34 which is angular 50 and preferably attached to the plate 15. Arranged within the socket 34 is a holder 35 embodying a pair of spring arms 36 which engage the socket 34 at opposite points, and may be turned at right angles to 55 the position shown in Figs. 6 and 10. The holder 35 carries an ink well 36a which is thus held in a convenient position and can be readily moved out of the way when not in actual use. 60

I claim as my invention:

1. In a chair, the combination with a back portion, of a front leg, a table supporting frame including a vertically arranged angle iron adjustably attached to said front leg, 65 a pair of rearwardly extending guides consisting of channel irons adjustably secured to the back portion and carried by said angle iron, and a table carrier including a vertically arranged plate provided with recessed 70 portions engaging the guides and adjustable laterally thereon.

2. In a chair, the combination with a back portion, of a front leg, a table supporting frame including a vertically arranged arm 75 adjustably attached to said front leg, a pair of rearwardly extending guides connected to the arm and adjustable vertically on the back portion, and a table carrier including a vertically arranged member or plate having engagement with said guides and adjustable laterally thereon. 80

CHARLES I. LATTIG.
